US0D1059410S

(12) **United States Design Patent** (10) Patent No.: **US D1,059,410 S**
(45) Date of Patent: ** Jan. 28, 2025

(54) **DISPLAY SCREEN OR A PORTION THEREOF WITH A GRAPHICAL USER INTERFACE**

(71) Applicant: **Lincoln Global, Inc.**, Santa Fe Springs, CA (US)

(72) Inventors: **Levi J. Mitchell**, Windsor, CO (US); **Jacob F. Aas**, Windsor, CO (US); **Camila Maria Perez Gavilan Torres**, Kitchener (CA); **Taylor L. Robertson**, Kitchener (CA); **Jeffrey T. E. Dugan**, Waterloo (CA); **Connor S. Sweet**, Waterloo (CA)

(73) Assignee: **LINCOLN GLOBAL, INC.**, Santa Fe Springs, CA (US)

(**) Term: **15 Years**

(21) Appl. No.: **29/894,300**

(22) Filed: **Jun. 8, 2023**

(51) LOC (15) Cl. **14-04**

(52) U.S. Cl.
